UNITED STATES PATENT OFFICE.

ANDREW FREDERIC STURM, OF NEHAWKA, NEBRASKA.

BED-SPRING AND AUTO-CUSHION.

1,389,168.

Specification of Letters Patent. Patented Aug. 30, 1921.

Application filed September 11, 1920. Serial No. 409,530.

To all whom it may concern:

Be it known that I, ANDREW FREDERIC STURM, a citizen of the United States, and a resident of Nehawka, in the county of Cass and State of Nebraska, have invented certain new and useful Improvements in Bed-Springs and Auto-Cushions, of which the following is a specification.

My invention is an improvement in bed springs and auto cushions and has for its object to provide an improved form of supporting spring arranged to obtain a maximum of resiliency and cushioning effect, and wherein means is provided in connection with the main spring, in the form of auxiliary springs arranged at the top of the main spring for holding the main springs in proper relation with respect to each other, while at the same time permitting them to yield laterally.

In the drawings:

Figure 1 is a top plan view of a portion of a mattress having the improved spring,

Fig. 2 is a section on the line 2—2 of Fig. 1,

Fig. 3 is a perspective view of one of the auxiliary springs,

Fig. 4 is a front view of one of the main springs.

In the present embodiment of the invention, the mattress is composed of a series of main springs, each consisting of two similar portions 1 and 1^a, connected by a coil 9. Each of these portions is a spiral coil, tapering from one end to the other, and the portions are arranged with their small ends adjacent. At the small end each portion has a radially extending arm 8, and these arms are connected by a coil 9. The arms 8 extend well outside of the spring, and each main spring is formed from a single piece of wire, all of the parts being integral.

One portion of each spring is connected to a slat 2 in the usual manner, by means of staples 3 or the like, and the coils 9 of the outermost spring constituting the mattress are engaged by wires or rods 4 which form a frame encircling the springs. These rods 4 as shown in Fig. 2, pass through the coils 9 of all of the outlying springs 1—1^a, the said coils of the said springs being spaced directly outwardly from the springs. The slats 2 are connected in any suitable manner to form a rigid support for the spring.

This arrangement provides a very resilient and elastic mattress. Each portion of each main spring is resilient, and the said portions are resiliently connected by means of the arms 8 and the coils 9.

With this construction, there is nothing to hold the tops of the springs 1 from lateral movement in every direction. The wires 4 are intermediate the ends of the springs 1, and hence do not support the tops of even the outermost springs. In order to overcome this objection, I connect adjacent springs by means of the auxiliary spring shown in Fig. 3. The said spring comprises a coil 5, having at each end an arm 6 extending laterally from the plane of the coil, and the outer end of each arm has a hook 7. These hooks 7 of the auxiliary spring are engaged with the topmost coils of the springs 1, thus connecting the said coils and connecting the springs. The arrangement is such that while the tops of the springs may move toward or from each other, they will, when deformed, return to normal position, under the impulse of the springs 5—6—7. Thus, increased flexibility, with increased resiliency is provided, and the mattress is longer lived because it does not get out of shape so easily under pressure.

I claim:

1. A mattress or cushion comprising a supporting frame, coiled springs seated on the frame, each spring consisting of two similar portions of greatest diameter at the outer ends and tapering toward their meeting ends, and connected by a coil offset radially from the axis of the spring, a frame passing through the offset coils of the outermost springs of the mattress and the other offset coils being free, and resilient connections between the outermost coils of the adjacent springs and similar connections between the corner spring and frame, said connections comprising a coil having at each end an arm provided with a hook for engaging the coils of the first named springs.

2. In a mattress or cushion, the combination with the supporting frame, of coil springs seated on the frame, each spring consisting of two similar portions of greatest diameter at the outer ends, and tapering toward their meeting ends, and connected by a coil offset radially from the axis of the spring, a frame passing through the coils

- of the outermost springs of the mattress, and resilient connections between the outermost coils of the adjacent springs.
3. In a mattress or cushion, the combination with the supporting frame, of coil springs seated on the frame, each spring consisting of two similar portions of greatest diameter at the outer ends, and tapering toward their meeting ends, and connected by a coil offset radially from the axis of the spring, a frame passing through the coils of

the outermost springs of the mattress and connections between the springs adjacent each other.

4. In a mattress or cushion, a spring consisting of two similar portions, each a spiral coil tapering toward its inner end, each portion having a radial arm at the said inner end and the arms being connected by a coil, said spring being of resilient material. 15

ANDREW FREDERIC STURM.
